UNITED STATES PATENT OFFICE.

HARRY SWINGLEHURST, OF LACONIA, NEW HAMPSHIRE, ASSIGNOR TO SCOTT & WILLIAMS, INCORPORATED, OF CAMDEN, NEW JERSEY, A CORPORATION OF NEW JERSEY.

DETECTOR DEVICE OF KNITTING-MACHINE STOP-MOTIONS.

1,099,408.

Specification of Letters Patent.

Patented June 9, 1914.

Application filed December 17, 1912. Serial No. 737,240.

To all whom it may concern:

Be it known that I, HARRY SWINGLEHURST, a citizen of the United States, and a resident of Laconia, in the county of Belknap 5 and State of New Hampshire, have invented a new and useful Improvement in Detector Devices of Knitting-Machine Stop-Motions, of which the following is a specification.

The object of my invention is to provide 10 an improved form of the device shown in the patent to Robert W. Scott and Harry Swinglehurst No. 679,641, granted July 30, 1901.

In the accompanying drawings, Figure 1 15 is a radial vertical section through so much of a rib knitting machine as is necessary to illustrate the application of my new device thereto, showing the detector device in side elevation, partly in section; Fig. 2 is 20 an end elevation of the standard and detector; Fig. 3 is a plan showing in dotted lines the position assumed by the detector element of the device when it has functionated.

25 In the machines of the type indicated the needle cylinder 2 and dial 3 are relatively stationary with respect to the machine table or bed plate 1, movement being given to the independent needles carried by each of the 30 needle carriers, the needle cylinder 2 and the dial 3, respectively, by cylinder cam 6, carried by a cam carrier 7, and by dial cams not shown, the ring or carrier 7 being the driven element through which movement is 35 imparted to the remainder of the cam structures.

On a support or standard 12 mounted on the ring 7, I provide as in the former patent a vertically movable drop bolt, or slide 40 18, which I have shown constructed as a round bar movable through holes in the lugs 13 projecting outwardly from the standard 12. Surrounding said bar and beneath the uppermost lug 13 is a light compression spring 14, the lower end of which 45 acts upon a washer 15 held in place by a pin 16 in a hole in the bolt 18.

Mounted to move in an annular groove in the bed plate 1 is a ring 30 having teeth 31 50 immediately beneath the lower end of the bolt 18. As in said patent, the ring 30 serves as a transmitter or actuator for the let-off and brake devices when it has been picked up and moved about the center of the

machine by the engagement therewith of the 55 bolt 18.

In the patented device the detector element, shown at 25 in said patent, is pivoted on the upper face of the standard 12, about a vertical pivot, so that upon the engagement of the working end thereof with a ball of waste or broken needle, substantially 60 on the line of intersection of the cylinder and dial needles, the device swings about said vertical pivot to withdraw a part thereof from a notch in the bolt 18 and permit it to actuate the ring 30. With this construction unless the adjustments in the machine are properly made, the outwardly 65 swinging movement of the detector, which 70 penetrates the path of the cylinder needles and takes place directly in the plane in which the dial needles move, will bring the detector into contact with the needles, and damage has at times been occasioned by the 75 presence of the point of the detector in these planes. Further difficulty has arisen from the tendency of the lever or detector shown in said patent to work out of the notch in the bolt, when there has been no 80 fault in the operation of the machine such as to actuate it. While the detector should be a sensitive instrument, it is very desirable that vibration or other causes short of the 85 condition which it is to detect should not affect it so as to cause the machine to stop unnecessarily.

In the structure shown in the drawings, the top of the standard 12 is inclined with respect to the axis about which the cam carriers rotate, as best shown in Fig. 2, so as to provide a wide bearing surface for the detector lever 25, which is inclined to the line of movement of the bolt 18. A shouldered screw 24 in a bore at right angles to the inclined face 26 of the standard 12 serves as a pivot for the lever 25, which is provided with an upstanding lug 27 and an edge 28. The bolt 18 is provided with a deep angular notch 33 in which the edge 28 is seated when 95 the lever 25 is in its adjusted position. The bottom of the notch 33 rests astride of the edge 28, to prevent the accidental turning of the bolt 18 upon its axis, thus avoiding the necessity for any special structure to 100 prevent rotation of the bolt. The stress of the spring 14 acting through the upper wall of the slot 33 on the edge 28 of the lever 25

holds said lever frictionally against the inclined face 26 of the standard 12, providing a sufficient resistance against accidental movement of the lever 25, without preventing its desired working movement. The seating of the lever 25 in the notch 33 is further aided by the disposition of the weight of the parts, the inner or detecting end of the lever 25 being slightly heavier than the inclined portion beyond the axis 24, enabling gravity to aid in positioning said members.

The detector point proper 32, which is made as a curved blade having a rounded and polished end reaching to the line of intersection of the needles, is attached to the lug 27 for vertical adjustment by a screw 29 in a longitudinally slotted hole in a vertical lug 34 of the point 32, which permits radial adjustment of the point of the device.

It will be noticed that the idle position of the lever 25 and the point 32 is in a plane intersecting the angle defined by co-operating cylinder and dial needles, and that the operative stroke of the detector carries it well out of the planes of the needles of both sets, where it is in no danger of being encountered by an abnormally advanced needle. The bolt 18 having been released by the detection of a fault, the blade 25 and point 32 can not return by gravity, or otherwise, to its adjusted position, owing to the unbroken upward extent of the bolt 18 above the notch 33, which prevents sufficient motion upon the pivot 24 to allow the lever to move so far. Re-setting of the device is accomplished by lifting the bolt 18 by hand.

What I claim is.

1. In a knitting machine having needle carriers and needles therein confined to movement on intersecting surfaces, a stop

motion device comprising a drop bolt, a detector contacting with said bolt to support it and having a part movable past the needles and near the line of intersection of the surfaces occupied by the needles, and a support upon which said detector is movable having a surface at an acute angle to the path of movement of said bolt, whereby said lever is frictionally held against its support to be moved by an obstruction at the needles and at an angle to the direction of movement of both sets of needles, to release said bolt.

2. In a stop motion device for knitting machines, comprising a drop bolt, let-off devices, and a connection actuated by said bolt to operate the let-off devices, in combination with a detector lever in contact with said bolt to restrain said bolt from movement, a support having a surface inclined to the path of movement of the drop bolt, upon which surface said lever is pivoted for movement toward and away from said bolt at an acute angle to said path of movement, said lever comprising means positioned to encounter an obstruction at the needles of the knitting machine.

3. In a stop motion device for knitting machines, a drop bolt, a lever mounted to swing about a pivot inclined with respect to the bolt, means on said bolt to engage said lever in one position, and a detector element vertically and horizontally adjustable upon said lever.

In testimony whereof, I have signed my name to this specification, in the presence of two subscribing witnesses.

HARRY SWINGLEHURST.
